UNITED STATES PATENT OFFICE.

FRANK XAVIER MUENZER, OF ELMORE, OHIO, ASSIGNOR TO THE MULTIPLEX CONCRETE MACHINERY COMPANY, OF ELMORE, OHIO, A CORPORATION OF OHIO.

BLOCK MACHINE.

Application filed August 5, 1927. Serial No. 210,756.

This invention relates to block forming apparatuses of the pressure type in which material such as concrete is poured into a forming box, and by means of pressure exerted on the material in the box the article is formed.

An object of this invention is to provide a simple and efficient forming apparatus which may be operated to press an article into shape and then automatically stop.

Another object is to provide in a block forming machine, new and improved means for satisfactorily pressing material into blocks.

Other objects and advantages will hereinafter appear, and the invention is shown by way of illustration in the accompanying drawings, in which:

Fig. 1 is a front elevation partly in section of a block-forming apparatus; Fig. 2 is a side elevation in section; and Fig. 3 is a sectional view of another portion of the apparatus.

The illustrated embodiment of the invention comprises a block-forming apparatus or machine having a frame provided with end walls 1 and 2 and side walls 3 and 4, the base of the frame being closed by a plate 5, thereby providing a receptacle to receive fluent lubricant so that the running parts of the apparatus operate in a bath of oil. Hingedly connected to the end wall 2 is a top plate or cover 6 which may be lifted to allow access to the operating parts. The inner or working parts of the machine are thus completely enclosed to prevent the entrance of dirt and grit, and the bath of oil provides for smooth running.

Mounted on the cover plate 6 and secured thereto by bolts is an open-ended block-forming box 7 to receive material, such as concrete. Plates 8 and 9 may be arranged within the box to provide blocks of different sizes and shapes, such plates being removable and held in place by guides or other suitable means.

Rising vertically from the frame are posts 10 to support at their upper end a hopper 11 in which is placed the material from which the blocks are to be formed. Pivotated to the lower end of the hopper is a spout 12 having an outwardly extending nose or discharge end 13 to rest upon the upper end of the forming box 7, the discharge end 13 having an opening to register with the upper

end of the box. A scraper 14 is slidable on rods 15 mounted on the discharge end of the spout for leveling the material discharged into the box 7.

Secured to the inlet end of the spout 12 is an arcuately-shaped part 15 which is positioned across the discharge end of the hopper 11 when the spout is lowered. This prevents the feeding of an excessive amount of material to the spout when the latter is discharging to the forming box. Upon movement of the spout upwardly, the part 15 swings outwardly to permit material to be discharged from the hopper into the spout, a baffle 16 guiding the material into the spout. For normally holding the spout 12 in raised position, a cable 17 is attached to the spout, passes over a sheave 18 and has a weight 19 secured to the opposite end.

The bottom of the forming box is closed by a pallet rest 20 which is movable into the box. After the box has been filled with suitable material, a tamping head 21 is swung to a position above the box, and by mechanism hereinafter described, the tamping head 21 is forced into the box to compress the material, and during the compressing action of the tamping head, the pallet rest is forced upwardly to press the material into a compact mass.

The tamping head 21 is made up of a cross bar 22 and vertical bars 23, a pressure plate 24 being attached to the cross bar 22 and adapted to be detached so that the design for the formed block may be changed at will. When swung to vertical position, the side bars 23 of the tamping head abut against stops 25 on the outside of the forming box 7.

The lower ends of the bars 23 are pivoted to arms 26 which are slidable vertically in guides 27. The lower ends of the arms 26 are pivoted to straps 28 which surround a driving shaft 29 suitably mounted in bearings in the side walls 3 and 4 of the frame. A set of bars or braces 33 are disposed on each side of the frame, and the arms 26 and straps 28 are likewise arranged on the outside of the frame. Fixed to the shaft 29 at opposite ends thereof are cams 30, one being positioned within each strap for forcing the tamping head 21 into the forming box, as will hereinafter be described.

The pallet rest 20 is carried by vertical bars 31 arranged at opposite ends of the rest, and the bars are vertically movable in

guides 32. The lower ends of the bars 31 rest upon cams 33 on the transverse shaft 29. The cams 30 and 33 are so constructed and arranged that during one revolution of the shaft 29 the tamping head is caused first to move into the forming box before the cams 33 effect an upward pressure upon the pallet rest 20. After approximately one quarter revolution of the shaft 29, the cams 33 force the pallet rest upwardly so that an equal pressure is exerted on the top and bottom of the mass within the forming or mould box 7. Thereafter, the pressure of the tamping head is gradually relieved, and the pallet rest 20 is forced a slight distance upwardly.

For holding the pallet rest in slightly raised position, the vertical bars 31 are formed with notches 34, into which 20 spring pressed plungers 35 are adapted to enter when the pallet rest has been raised the required distance. This holds the block in position prior to ejection.

The driving shaft 29 for the tamping head 25 and pallet rest is operated from a power shaft 36 arranged above the shaft 29 and provided with a pinion 37 which is adapted to mesh with a gear 38 on the shaft 29. A pulley wheel 39 on the shaft 36 may be connected with a suitable source of power, a cone clutch 40 may connect the wheel 39 and shaft 36, an operating lever 41 being connected to the frame by a link 42 for moving the clutch 40.

35 A suitable clutch 43 controls the pinion 37 which is slidable on the shaft 36, the clutch 43 being carried by a spring pressed shaft 44, which tends normally to hold the clutch in position to retain the pinion 37 out 40 of engagement with the gear 38, a suitable spring (not shown) tending to force the pinion into engagement with the gear 38. The form of clutch constitutes no part of the present invention, and the above is deemed sufficient to enable those skilled in 45 the art to understand the construction and operation.

It is desired that the apparatus so operate 50 that material be compressed into block form, and thereafter stop and necessitate a manual operation on the part of the operator before it will again function. For this purpose, a cam 45 is fixed to the driving shaft 29 and is formed with a recessed part 46. Rotatable 55 on the cam 45 is a roller 47 carried by a pedal lever 48 having a foot piece 49 extending outside of the frame. The lever 48 is suspended from a transverse shaft 50 and is connected to the clutch lever 44, a coil spring 60 51 holding the lever in such position that the roller 46 always bears against the cam 45.

In operation, when the pedal lever 48 is depressed, the clutch 43 releases the pinion 65 37 which engages the gear 38 for rotation thereof. After the control cam 45 has made

a complete revolution, the roller 47 is drawn upwardly by the spring 51 into the recessed portion 46 which allows the clutch 43 to be raised by the spring pressed stem 44 and disengage the pinion 37 from the gear 38. 70 The driving shaft 29 is therefore given one complete revolution, and is thereupon disconnected from the power shaft 36, the latter rotating continuously.

In order to completely eject the finished 75 block, the lower ends of the pallet rest bars 31 are provided with pins 52 which project into elongate slots 53 in levers 54 pivoted intermediate their ends on shafts 36. The opposite ends of the levers 54 are connected 80 by links 55 to arms 56 fixed to a shaft 57. Keyed to the outer end of the shaft 57 is a lever 58. By movement of the lever 58 in one direction, it is apparent that the pallet rest 20 is moved upwardly, thereby to eject 85 the block. To enable the block to be ejected the tamping head 21 is first swung to one side of the forming box, as shown in Fig. 2.

It is manifest that I have produced an 90 efficient block forming machine which can be readily operated for making satisfactory blocks with a minimum amount of trouble and labor. The number of moving parts is reduced to a minimum, and the majority of parts are enclosed and run in a bath of lubricant. By virtue of the construction and arrangement, a great pressure can be developed on opposite sides of the material for 95 thoroughly compacting the same.

It is to be understood that my machine 100 may be used in other connections than block forming, and numerous changes in details of construction and arrangement may be effected without departing from the spirit of the invention, especially as defined in the 105 appended claims.

What I claim as new and desire to secure by Letters Patent is:

1. In a block forming machine, a forming box, a tamping head movable into the box 110 from the upper end thereof, a pallet rest for the bottom of the box, means forcing said tamping head into the box, and means to force the pallet rest toward said tamping head during the latter portion of movement 115 of the head and to continue such movement after the movement of the head has been discontinued and reversed, thereby partially to eject the block from the forming box.

2. In a block forming machine, a forming box, a tamping head and pallet rest on opposite ends of the box, means to force said head into said box, and means to force the pallet rest toward the head first to compress the material, and subsequently partially to 125 eject the formed block from the box.

3. In a block forming machine, a forming box, a tamping head and pallet rest on opposite ends of the box, means to force said head into said box, and means to force the 130

pallet rest toward the head first to compress the material, and subsequently partially to eject the formed block from the box, said means being operated from a common drive shaft.

4. In a block forming machine, an open ended forming box, a pallet rest for the bottom of said box, a tamping head movable into the upper end of said box, cam means for moving the tamping head into the box, means for forcing the pallet rest toward the tamping head, and partially ejecting the formed block, and means for further moving the pallet rest completely to eject the block.

5. In a block forming machine, a forming box, a tamping head straddling said box and movable therein, a pallet rest providing the bottom of said box, means for moving said head, means for moving said rest relatively and conjointly with respect to said head for compressing material in the box and partially ejecting the formed block, means to releasably hold the pallet rest in partially ejected position, and means to complete the ejection of the formed block.

6. In a block forming machine, a box, a pallet rest forming the bottom of the box, cam means for raising said pallet rest a predetermined distance, means for releasably holding said pallet rest in such raised position, and manual means separate from said cam for discharging the formed block from the box.

7. In a block forming machine, an open ended forming box, a tamping head, having parts straddling said box and mounted to be swung to one side thereof, a movable bottom for said box, a power shaft, a driving shaft connected to be driven from said power shaft, cam means on said driving shaft for forcing the tamping head into the box, means for elevating the movable bottom during a portion of the movement of said head and conjointly elevating both bottom and head, control means on said driving shaft, and a connection between said control

means and said power shaft for automatically disconnecting the driving shaft from the power shaft after a predetermined movement of the former.

8. In a block forming machine, an open ended forming box, a tamping head having parts straddling said box and mounted to be swung to one side thereof, a movable bottom for said box, a power shaft, a driving shaft connected to be driven from said power shaft, cam means on said driving shaft for forcing the tamping head into the box, means for elevating the movable bottom during a portion of the movement of said head and conjointly elevating both bottom and head, releasable means for holding said bottom in such raised position, control means on said driving shaft, and a connection between said control means and said power shaft for automatically disconnecting the driving shaft from the power shaft after a predetermined movement of the former.

9. In a block forming machine, an open ended forming box, a tamping head having parts straddling said box and mounted to be swung to one side thereof, a movable bottom for said box, a power shaft, a driving shaft connected to be driven from said power shaft, cam means on said driving shaft for forcing the tamping head into the box, means for elevating the movable bottom during a portion of the movement of said head and conjointly elevating both bottom and head, releasable means for holding said bottom in such raised position, manually operable lever means for further elevating said movable bottom, thereby to eject the formed block, control means on said driving shaft, and a connection between said control means and said power shaft for automatically disconnecting the driving shaft from the power shaft after a predetermined movement of the former.

In testimony whereof I have hereunto signed my name to this specification.

FRANK XAVIER MUENZER.
